UNITED STATES PATENT OFFICE.

MAXIMILLIAN A. MILLER, OF BALTIMORE, MARYLAND.

GAME DEVICE.

Application filed March 2, 1922. Serial No. 540,384.

To all whom it may concern:

Be it known that I, MAXIMILLIAN A. MILLER, a citizen of the United States, residing at Baltimore city, in the State of Maryland, 5 have invented certain new and useful Improvements in Game Devices, of which the following is a specification.

This invention relates to game devices, and specifically, to a combined game of skill 10 and chance.

One object of this invention is to provide a game device that is partly automatic in its operation, the automatic parts being co-operative with the manually operable parts 15 in such manner that their combined effect very nearly simulates the U. S. national game, base ball.

Another object of the invention is to provide an improved form of game board or 20 field with means for determining the percentage of operation; that is, approximate percentage of profit accruing to the operator for a given sum collected as fees or tolls.

A further object of the invention is to 25 provide a game board of this character with a traveling unit or member, means for detaining this member at a starting point or station, and means to vary the paths of travel of this member so that it may chance 30 to end its travel at any one of any appropriate number of goals or divisions of a goal.

A further object of this invention is to so modify the game of skill disclosed in Patent No. 1,203,852 (issued Nov. 7, 1916) 35 or any similar game device, and to so correlate and connect my game-board or field therewith, that they co-operate to produce a combined skill and chance game which may take form as a base ball game or other game.

40 A further object is to provide a plurality of racers, an automatic means for registering or indicating the winning racer, a goal representing each racer, and a traveling member common to all these racers, this 45 traveling member being automatically releasable from a starting station by the winner of the racers, and when released, will travel to and stop on one of these goals.

Other objects and advantages will be 50 pointed out or implied in connection with the accompanying drawings in which—

Fig. 1 is a sectional view along the line 1—1 of Fig. 2.

Fig. 2 is a sectional view along the line 55 2—2 of Fig. 1.

Fig. 3 is a horizontal sectional view along the line 3—3 of Fig. 2.

Fig. 4 is a detail view of a part of the operating and controlling mechanism.

Fig. 5 is a top plan view of my improved 60 game-board or field.

Fig. 6 is a vertical sectional view of the game board, the section being taken along the line 6—6 of Fig. 5, the electrical parts being diagrammatic.

Fig. 7 is a detail view of one of the goals or goal-sections slightly different from that shown in Fig. 5.

Fig. 8 is an elevation of a gun or ball placer such as described in Patent No. 70 1138865, or of any appropriate construction, in connection with a tube or track along which the ball or traveling member passes to its starting station.

Fig. 9 is a somewhat diagrammatic view 75 of an electric switch mechanism by which the racers control the annunciating and profit-registering or value registering member, also the electrical adjuncts.

Fig. 10 is a sectional view along the line 80 10—10 of Fig. 9.

Fig. 11 is a detail view of a governing or controlling mechanism which may be employed in connection with or in lieu of certain governing elements shown in Fig. 4.

Referring to these drawings in detail, in 85 which similar reference characters correspond to similar parts throughout the several views; the invention consists, in the construction and arrangement or combination of devices which will now be fully described; but I will first give a general description of the structure defined by the above mentioned Patent, No. 1203852, as

modified to form part of a base ball game 90 device: That patent shows and refers to "a number of units such as carriages, dolls, horses or the like" adapted to be "propelled along a race course by the manipulation of a corresponding number of hand wheels, 100 each operator or player striving to be first to bring his unit to the winning post and thereby win the race." It is stated, as an object of that invention, that the object "is to render such device more attractive and 105 entertaining by enabling the units to get out of control of the operators under certain conditions and remain stationary or actually turn and move in a direction away from the winning post." Moreover, that "the 110

units are adapted to be freed or disconnected from their corresponding hand wheels when the speed of rotation of the latter exceeds a predetermined value, so they remain 5 stationary or actually turn and move in an opposite direction out of the control of the operators or players." Also, that "when the race has been won by one of the units, the attendant is able to disconnect all the units 10 from the hand wheels, so that they may automatically return to the starting point. 'In a similar manner when the race is to be started, the attendant can connect the units to the corresponding hand wheels.' 15 For the sake of clearness, the word unit will be hereinafter employed in the specification to designate the member which traverses the course but it is to be understood that such term is intended to cover a carriage, horse, 20 doll or any other figure that may be used with the device." The foregoing features also apply to the present invention.

Details of the foregoing and of my modifications are as follows: The traveling or 25 racing units, in the present instance, are represented at 1 as dolls or puppets in imitation of base ball players. Each of these is preferably mounted on a springy or yielding element 2 which is united with a pivot 30 3, the latter being united with a sheave or wheel 4 having lines or cables 5 and 6 connected thereto and adapted to operate thereon in the manner described in connection with Fig. 6 of the Clorius Patent, No. 35 1203852, above referred to. The pivot 3 is journaled in a carriage 7 which is caused to travel along a track or course 8 by means of the lines 5 and 6 and the correlated means shown in Fig. 1 of these drawings, but 40 shown separately in Fig. 1 of the Clorius Patent (above referred to).

At the end of this track or race-course is a special switch mechanism which forms 45 part of an electric circuit. This circuit is shown diagrammatically in Fig. 9, and includes a battery or other electric generator, lamps 10, and solenoids or other electrically controlled elements 11 and 12, also a conducting base or plate 13 to which the 50 switches 14 and 15 are secured and to which the battery is grounded at 16. There may be any appropriate number of the switches 14 and any appropriate number of the units 1, but there must be at least one switch 55 14 for each unit 1, and there is a universal switch 15, that is, one switch which is common to all the switches 14 and operable or controllable by any one of these separately operable and independent switches 14. Referring to Figs. 9 and 10, it is seen that 60 each switch 14 includes a movable member 17 and a fixed member 18, the latter being mounted on an insulation 19 which is supported on uprights 20 that are united with 65 the plate 13, and a spring 21 is provided

for each switch 14, to hold it in open relation. Each switch-element 17 is provided with a forward extension against which the corresponding figure or unit 1 is adapted to strike when it reaches the end of the race 70 or track. A notch 22 (of each unit 1) may receive the front end of the member 17 so that the operation of the switch by this unit is assured when the unit thus engages the switch while being propelled by the mechanism hereinafter described in connection with the line 6. As the member 17 is swung to the switch-closing position by the unit 1, the spring 2 yields to permit an upward 75 movement of the member 1. The spring 2 and the springy upper part of the switch member 17 (of each switch 14) co-operate to cushion the impact of the unit 1 against the switch.

The universal switch 15 includes a bar 85 or beam 23 and an arm 24 as the movable switch-member, and an element 25 as the fixed switch member, the latter being mounted on the insulation 19, while the member 23-24 is pivoted at 26 to the uprights 20, 90 insulating bearings 27 being provided to prevent electrical connection of the member 23-24 with the plate or base 13. The bar 23 is in the path of all the switches 14, so that any one of the latter will close the switch 95 15 when this switch is itself being closed. A spring 28 bears against a suitable insulation 29, on the bar 23, so as to return the switch 15 to the open position.

Each of the lamps 10 is electrically connected to a conducting wire 30 and to a corresponding one of the switch members 18, the wire 30 being a part of the electric circuit above referred to. The arrangement is such that if all the switches were closed 105 at the same time, the lights would be connected in parallel. They may be thus considered and claimed, as it is not impossible for all the units 1 to reach the end of the race simultaneously, thus closing all the 110 switches 14, though such is not likely to occur. The lights 10 may be various colors, and these colors may correspond to those of my game board, as indicated by symbols. By means of these lights, the result of the 115 race may be indicated or announced, and to render this enunciation more graphic, the units 1 may be of different colors to correspond to those of the lights. This correlation of colors of the lights, racing units 120 and goals of the game board, enables each operator or player to be identified graphically with the racing units and the value-indicating goals which will presently be described in detail.

Referring now to Figs. 1 and 5, my improved game-board 31 is forwardly and downwardly inclined, being supported above the tracks 8 by means of posts 32 or other appropriate means. A starting station 33 125

for a ball or other traveling member 34 this device used as a base ball game, the may be provided with a track or tube 35 goal-stops 1, 2, 3 and 4 may indicate, re- for conducting the ball or member 34 there- spective, a run to first base, to second into from the hand of a person at a dis- base, to third base, or to the home plate. 5 tance from the starting point or station 33. The station 33 represents the batters' plate, 70 A gun 36 such as shown in Fig. 8, or in Fig. 2 of the Hagerty Patent No. 1138865, may be connected with the tube 35 so as to shoot the ball 24 through the latter into the 10 hopper or starting station 33, or any other appropriate means may be used for putting the ball in the starting station. The hopper or station 33 has an outlet, preferably a chute 37, provided with a closure or detent 15 38 which detains the ball or member 34 against leaving the starting station. The closure or detent 38 may be hinged at 39 and provided with a weight 40 which closes the closure but permits it to swing open, 20 under pressure or weight of the member 34 thereagainst, when the closure or detent is released from an electrically operated latch 41. The latter is an extension of a solenoid- core which is drawn away from the detent 25 38 by the solenoid 11. A spring 42 may be provided to hold the latch in engagement with the detent 38 when the solenoid 11 is not energized. More broadly considered, the elements 38 to 41 inclusive may con- 30 stitute the detent, or this detent may be of any appropriate construction. As seen in Fig. 9, the solenoid 11 is interposed in the electric conductor 30 or forms a part of this conductor, so that it is energized as soon as 35 any one of the switches 14 closes the switch 15. Therefore, as soon as the race has been won by any unit 1, the ball 34 is immediately released from its detaining means and starts rolling down the game-board to- 40 wards the goal or goal-sections 42. While thus rolling or traveling, it encounters numerous staggered pins or studs 43 which may broadly be termed deflectors, for they deflect the member 34 from side to side, so 45 that it is as likely to stop at one part of the goal as another. It may also stop in different parts of any particular goal-section, and thus it indicates different values, as will presently appear.

50 Referring now to Figs. 5 and 7, it will be seen that each goal-section 42 is subdivided by the provision of a row of pins or studs 44 which are spaced a distance less than the diameter of the ball 34, and 55 therefore, the ball will lodge in one of the spaces between two pins or goal-stops 44, resting against two of these goal-stops. These destinations of the ball (after traveling from the station 33) represent different 60 values, for instance, 1, 2, 3 and 4, respectively, as shown in Fig. 7, while the larger numeral 3 of this figure and the numerals or ordinals 1 to 9 of Fig. 1 may be used in lieu of or in connection with the different 65 colors to identify the respective players. In

this device used as a base ball game, the goal-stops 1, 2, 3 and 4 may indicate, re- spective, a run to first base, to second base, to third base, or to the home plate. The station 33 represents the batters' plate, 70 and, of course the ball 34 represents the base ball, and the units 1 represent the base-runners. The diamond 45 and pitcher's stand 46 merely lend a realistic appearance to the game-board, as imitating a base ball 75 field.

Referring again to the operating mechanism shown in Figs. 1 to 4 and to the detail description thereof in the Clorius Patent No. 1203852, a more general or less 80 detailed description is here given as follows:

There is one of these operating mechanisms for each one of the units 1, and these mechanisms are separately and independently operable by hand-wheels or actuators 85 47 which may be considered as parts, respectively, of the operating mechanisms. Each hand-wheel is geared to a pulley 48 through the medium of a shaft 49 (or two axially 90 alined shafts, Fig. 11), two intermeshing gears or wheels 50 and 51, and two alined shafts 52 and 53 which are provided with a clutch 54 for locking them together, or free- 95 ing the shaft 53 from control of the shaft 52. Each of these clutches is provided with an operating and controlling member 55, and all of these members are elastically mounted for radial movement on a shaft 56, but being non-rotatable with respect to the 100 shaft 56, so that when any one of these members 55 is operated the others are thereby operated in the same manner. One of these members is provided with an operating lever or handle 57 having three operative 105 positions, viz, the rightward position (Fig. 3), the leftward position and the central position. When the lever 57 is in the central position, it frictionally engages the clutch member 54 and holds it out of clutch- 110 ing relation with a radial stud 58 of the shaft 53, at the same time causing the sleeve 54 to frictionally engage the shaft 53 and exert a braking action to prevent retrograde movement of the shaft 53. This braking 115 action is relieved by shifting the lever to the leftward position in which it continues, however, to hold the sleeve 54 and stud 58 disengaged so the shaft 53 can have retro- 120 grade movement for permitting all the units 1 to return to their starting place, as will presently be shown. When the lever is moved to the rightward position, it throws all the sleeves 54 into engagement with the respective studs 58, thereby locking all the 125 pairs of alined shafts 52 and 53 together, the sleeves 54 being non-rotatably secured to the shafts 52. The lever 57 is preferably held in the central position by a pair of equalizing springs 59, and one of these 130

4 springs automatically shifts the lever from the rightward position to the central position immediately upon the arrival of any one of the units 1 to the end of the race. 5 Until the arrival of a winning unit at the end of the race, the lever 57 is held in the rightward position by an electrically controlled detent or lever 60 pivotally mounted at 61. The same is shown in detail in Fig. 9. 10 It may be provided with a spring 62 for holding it in the detaining position, and its detaining end may be beveled at 63 to permit the lever to slide thereon into its detained engagement. One end of the lever 15 60 is provided with a solenoid-core 64 which co-operates with the solenoid 12 for swinging the lever 60 out of engagement with the lever 57 when the switch 15 is closed by any one of the switches 14. It is evident, 20 therefore, that when any one of the units 1 reaches the end of the race and closes the corresponding switch 14, this unit and all the other are automatically stopped, so the players may properly inspect the relative 25 positions of these units for definitely deciding whether the indicated first winner is the real or actual first winner, also decide which has second and third place in the race. When this has been decided to the 30 satisfaction of all players, the lever 57 can be swung to the leftward position, thereby releasing the shaft 53 and permitting it to turn backward under the impulse of a weight 65 on the line 5 (Fig. 1). The structure 35 whereby the units 1 are caused to "face about" while returning is clearly described in the said Clorius patent, also the connection of the line 6 with the drum or pulley 48 whereby the latter winds the line 6 there- 40 on so as to pull the unit 1 along the track 2. Of course there is a line 6 and a drum 48 for each unit 1.

Each operating and controlling mechanism may be provided with or include a 45 sheave 66 such as shown at S in the Clorius patent, also the adjacent spring and threaded connection for controlling this sheave, and the drum 48 may be provided with the yielding detent 67 for engaging and disengaging the radial stud of the shaft 53 according to the relative speed of the shaft 53 and that of the hand-wheel 47, as turned by the player. However these members may be 50 eliminated when the motor 68 is not used to drive the shafts 53; although I may employ the motor for operating these shafts in the manner described in the Clorius patent; but when the motor and its connections with the shaft 53 are not used, I may employ the governing or controlling mechanism shown in 55 Fig. 11, wherein each hand-wheel 47 is mounted on a shaft 49^a which is alined with a shaft 49^b, the latter carrying the gear wheel 50. A sleeve or clutch-member 69 is notched 60 for engagement with radial studs 70 of the

shaft 49^b. This sleeve is movable up and down on the adjoining ends of these shafts by means of a ball-governor of ordinary form, the governor-arms being pivoted to a member 71 which is fixed to the shaft 49^a. 70 With this simplified construction, the respective operating mechanisms operate entirely independently of one another and of any power other than manual power, and when any player turns his wheel 47 too fast, 75 the governor-sleeve 69 is raised out of engagement with the studs 70 so that the shaft 49^b begins to turn backwards, under the influence of the weight 65; but if the operator or player now stops or slows down, the sleeve 80 will again engage the studs 70 and stop the retrograde movement of the shaft 53 and the unit 1 connected thereto. Guiding pulleys or sheaves 72 and 73 are provided for the respective lines 5 and 6, and guiding and 85 tightening pulleys 74 are provided for a belt 75 which connects the sheaves 66 to the motor 68 when these elements are used.

All the parts above mentioned may be, and are preferably, supported by and within 90 a housing 76 provided with a platform 77 behind a bar or barrier 78, the latter separating the players from the attendant who operates the lever 57.

It is not intended to limit this invention 95 to the exact details of construction and operation here described and shown, but numerous changes may be made within the scope of the inventive ideas as implied and claimed. 100

What I claim as my invention is:

1. In an amusement device, the combination of a unit, a course along which said unit is adapted to travel, a hand-operated member for displacing said unit along the course, 105 means for releasing the operative connection between said hand-operated member and unit when the speed of the hand-operated member exceeds a predetermined value, a game-field distinct from said course, a game member to travel said game-field, means to detain the said game-member, and means controllable by said unit to release said game member. 110

2. In an amusement device, the combination of a unit, a course along which said unit is adapted to travel, a hand-operated member for displacing said unit along the course, means for releasing the operative connection between said hand-operated member and the unit when the speed of the hand-operated member exceeds a predetermined value, means for imparting a turning movement to said unit so that it faces the opposite direction and remains at rest when the operative connection between the hand-operated member and unit is released, a game-field distinct from said course, a game member to travel said game-field, means to detain the said game-member, and means controllable by said unit to release said game member. 125 130

3. In an amusement device, the combination of a number of units, a course along which said units are adapted to travel, hand operated members for displacing said units along the course, means for releasing the operative connection between said hand operated members, and units when the speed of the hand operated members exceeds a predetermined value, a game-field distinct from said course, a game member to travel said game-field, means to detain the said game-member, and means controllable by a plurality of said units for releasing said game member.
4. In an amusement device, the combination of a number of units, a course along which said units are adapted to travel, hand operated members for displacing said units along the course, means for releasing the operative connection between said hand operated members and units when the speed of the hand operated members exceeds a predetermined value, means for imparting a turning movement to said units so that they face the opposite direction and remain at rest when the operative connection between the hand wheels and the units is released, a game-field distinct from said course, a game member to travel said game-field, means to detain the said game-member, and means controllable by a plurality of said units for releasing said game member.
5. In an amusement device, the combination of a number of units, a course along which said units are adapted to travel, hand wheels for displacing said units along the course, means for releasing the operative connection between said hand wheels and units when the speed of the hand wheels exceeds a predetermined value, means for imparting a turning and retrograde movement to said units when the operative connection between the hand wheels and units is released, a game-field distinct from said course, a game member to travel said game-field, means to detain the said game-member and means controllable by a plurality of said units for releasing said game member.
6. In an amusement device, the combination of a race course, a plurality of units adapted to move along said course, a plurality of slides on which said units are mounted so as to be capable of angular displacement, hand wheels for displacing said units along the course, clutches arranged between said hand wheels and units for releasing the operative connection between said parts when the speed of the hand wheels exceeds a predetermined limit, means for imparting a turning and retrograde movement to said units when the operative connection between the hand wheels and units is released, a game-field distinct from said course, a game member to travel said game-field, means to detain the said game-member,
- and means controllable by a plurality of said units for causing the detaining means to release said game member.
7. In an amusement device, the combination with a race course, of a plurality of units adapted to traverse said course, a plurality of falling weights, means for connecting said weights to the units, a plurality of winding drums, means for operatively connecting said winding drums to said units, a plurality of hand wheels, clutches for operatively connecting said hand wheels to the winding drums, means for automatically controlling the operative connection between the hand wheels and winding drums so as to release the connection when the speed of the hand wheels exceeds a predetermined value and remake the same when the speed is again brought within the limit speed, a game-field distinct from said course, a game-member to travel said game-field, means to detain the said game-member, and means controllable by a plurality of said units for causing the detaining means to release said game member.
8. In an amusement device, the combination with a race course, of a plurality of units adapted to traverse said race course, a plurality of falling weights, means for connecting said weights to the units so that they tend to maintain the units at the starting end of the course, a plurality of winding drums for moving the units to the opposite end of the course, cords for operatively connecting said drums to the units a plurality of hand wheels, clutches for operatively connecting said hand wheels to the winding drums, continuously rotating members adapted to automatically release said clutches when the speed of the hand wheels exceeds a predetermined speed dependent on the speed of said continuously rotating members, a game-field distinct from said course, a game member to travel said game-field, means to detain the said game-member and means controllable by the plurality of said units for causing the detaining means to release said game member.
9. In an amusement device, the combination with a race course, of a unit adapted to travel along said course, a falling weight, means for connecting said weight to the unit so that it tends to maintain the unit at the starting end of the course, a winding drum for moving the unit to the opposite end of the course, a cord for operatively connecting said winding drum to the unit, a hand wheel, a clutch for operatively connecting said hand wheel to the winding drum, a continuously rotating member adapted to automatically release said clutch when the speed of the hand wheel exceeds a predetermined speed dependent on the speed of the said continuously rotating

member, a game-field distinct from said course, a game member to travel said game-field, means to detain the said game-member, and means controllable by said unit to cause the detaining means to release said game member.

10. In an amusement device, the combination of a race course, of a slide adapted to be drawn along said course, a spindle journaled in said slide, a pulley fixed on the said spindle, a cord wound on and attached at one end to the circumference of the said pulley, a winding drum connected to the other end of said cord, a hand operated member, a clutch for operatively connecting the hand operated member with the said drum, a sheave driven at a constant speed and adapted to release the said clutch when the speed of the said hand operated member exceeds a predetermined speed dependent on the speed of the said constantly driven member, a falling weight, a cord connecting said weight to the pulley of the spindle of the slide and adapted to turn said spindle through half a revolution when the said clutch is released, a game-field distinct from said course, a game member to travel said game-field, means to detain the said game-member, and means controllable by said slide to cause said detaining means to release said game member.

11. In an amusement device, the combination with a race course, of a number of slides adapted to be drawn along said course, spindles journaled in said slides, pulleys fixed on said spindles, cords wound on and attached at one end to circumferences of said pulleys, winding drums connected to other ends of said cords, hand operated members, clutches for operatively connecting said hand operated members with said drums, sheaves driven at a constant speed and adapted to release said clutches when the speed of the hand operated members exceeds a predetermined speed dependent on the speed of said constantly driven members, falling weights, cords connecting said weights to the pulleys of the spindles of the slides and adapted to turn said spindles through half a revolution when said clutches are released, a game-field distinct from said course, a game member to travel said game-field, means to detain the said game member, and means controllable by a plurality of said slides for causing the detaining means to release said game member.

12. In an amusement device, the combination with a race course and a unit to travel thereon, of a hand operated shaft, a clutch for connecting said shaft with said unit, a sheave adapted to freely revolve on said shaft, a motor for driving said sheave at a constant speed, a thread in the hub of said sheave, a thread on the hand operated

shaft adapted to engage the thread of the hub of the sheave when the speed of said shaft exceeds that of the sheave, so as to disengage said clutch, a game-field distinct from said course, a game member to travel said game-field, means to detain the said game-member, and means controllable by said unit to cause said detaining means to release said game member.

13. In an amusement device, the combination with a race course, of a number of units, hand operated shafts, clutches for connecting said shafts with the units, sheaves adapted to freely revolve on said shafts, motors for driving said sheaves at a constant speed, threads in the hub of said sheaves, threads on the hand operated shafts adapted to engage the threads in the hubs of the sheaves when the speed of the said shafts exceeds that of the sheaves, so as to disengage said clutches, a game-field distinct from said course, a game member to travel said game-field, means to detain the said game-member, and means controllable by a plurality of said units for causing the detaining means to release said game member.

14. In an amusement device, the combination with a race course, of a number of units adapted to traverse said course, a plurality of hand operated shafts, a plurality of winding drums mounted on said shafts, a plurality of clutches for operatively connecting said drums to the shafts, a plurality of continuously rotating sheaves arranged adjacent said drums and in abutment therewith, internal threads in the hubs of said sheaves, threads on the shafts adapted to engage with said internal threads when the speed of the shafts exceeds the speed of the sheaves, so as to withdraw said sheaves from abutment with the winding drums and permit the same being disconnected with the driving shafts, a game-field distinct from said course, a game-member to travel said game-field, means to detain the said game-member, and means controllable by a plurality of said units for causing the detaining means to release said game member.

15. In an amusement device, the combination with a race course, of a plurality of slides adapted to move along said course, angularly displaceable spindles carried by said slides, units mounted on said spindles, pulleys carried by the lower ends of said spindles, a plurality of falling weights, cords for connecting said weights to the pulleys, a plurality of hand wheels, a plurality of driving shafts, means for operatively connecting said hand wheels to the driving shafts, a plurality of driven shafts coaxial with said driving shafts, a plurality of clutches for connecting and disconnecting said coaxial shafts, a plurality of wind-

- ing drums mounted on said driven shafts, cords for enabling said winding drums to displace the slides along the course and incidentally head the same in the right direction, means for clutching said drums to the driven shafts, a plurality of members rotating at constant speed adjacent to said drums and tending to turn the latter in the same direction, internal threads in 5 the hubs of said sheaves, threads on the driven shafts which are adapted to enter the threads in the hubs of the sheaves when the speed of the driven shafts exceeds that of the sheaves so as to latterly displace 10 said sheaves and allow of the winding drums being disconnected from the driven shafts, a game-field distinct from said course, a game member to travel said game-field, means to detain the said game-member, and means controllable by a plurality of 15 said units for causing the detaining means to release said game member.
16. In an amusement device, the combination of a main structure including a 20 course, a plurality of units adapted to travel said course, a table united with said main structure, hand-operated means over or substantially on the table and provided with means to control the travel of said 25 units, a platform united with the main structure and disposed between said table and units, the last said means extending under the platform and connecting the hand operated means with the said units, 30 a game-field supported by said main structure, a game-member to travel said game-field, means to detain said game-member, and means controllable by a plurality of 35 said units for causing the detaining means to release said game member. 40
17. In an amusement device, the combination of a main structure including a course, a plurality of units adapted to travel over said course, a table united with 45 said main structure, hand operated means arranged on said table, shafts extending angularly from said table and each connected with one of said hand operated means, power transmitting means extending 50 from each of said shafts, and means disposed in said main structure and connected with said units and also connected with said power transmitting mechanism, whereby operation of said hand operated means 55 controls the travel of said units, a game-field supported by said main structure, a game member to travel said game-field, means to detain the said game-member, and means controllable by a plurality of 60 said units for causing the detaining means to release said game member. 65
18. In an amusement device, the combination of a plurality of units, a course along which said units are adapted to travel, a 70 plurality of hand operated means remote from said course and disposed in alinement parallel thereto, means providing a passageway between said hand operated means and said course, means for operatively connecting said hand operated means with the units for displacing the same along the course, a game-field distinct from said course, a game member to travel said game-field, means to detain the said game-member, and means controllable by a plurality of 75 said units for causing the detaining means to release said game member. 80
19. In an amusement device, the combination of a plurality of units, a course along which said units are adapted to travel, a plurality of hand operated means for displacing said units, a manually operated member for simultaneously clutching all of 85 said hand operated means with said units, a game-field distinct from said course, a game member to travel said game-field, means to detain the said game-member, and means controllable by a plurality of said units for causing the detaining means to release said game member. 90
20. In an amusement device, the combination of a plurality of units, a course along which said units are adapted to travel, a plurality of hand operated means for displacing said units, a manually operated member for simultaneously unclutching all 95 of said hand operated means from said units, a game-field distinct from said course, a game member to travel said game-field, means to detain the said game-member, and means controllable by a plurality of 100 said units for causing the detaining means to release said game member. 100
21. In an amusement device, the combination of a plurality of units, a course along 105 which said units are adapted to travel, a plurality of hand operated means for displacing said units, a hand operated member for simultaneously connecting all of said hand operated means with the units, means 110 for simultaneously disconnecting all of said hand operated means from the units, a game-field distinct from said course, a game member to travel said game-field, means to detain the said game-member, and means 115 controllable by a plurality of said units for causing the detaining means to release said game member. 120
22. In an amusement device, the combination of a plurality of units, a course along 125 which said units are adapted to travel, a plurality of hand operated means for displacing said units, a hand operated member for simultaneously disconnecting said hand operated means from the units, automatic means for imparting a retrograde movement to said units, a game-field distinct from said course, a game member to travel said game-field, means to detain the said game-member, and means controllable 130

by a plurality of said units for causing the detaining means to release said game member.

23. In an amusement device, the combination of a main structure including a course, a plurality of units adapted to travel over said course, a table arranged at a distance from said course, hand operated means upon said table for controlling the travel of said units, a platform between said table and said units, normally disestablished means extending beneath said platform for connecting said hand wheels with said units, a manually operated member in proximity with said table for establishing said connecting means between the units and the hand operated means, a game-field distinct from said course, a game member to travel said game-field, means to detain the said game-member, and means controllable by a plurality of said units for causing the detaining means to release said game member.

24. In an amusement device, the combination of a unit, a course along which said unit is adapted to travel, a hand operated means for displacing said unit, means operable at a predetermined speed of operation of said hand operated member for automatically controlling the speed of travel of the aforesaid unit, a game-field distinct from said course, a game member to travel said game-field, means to detain the said game-member, and means controllable by said unit for causing the detaining means to release said game member.

25. In an amusement device, the combination of a unit, a course along which said unit is adapted to travel, means for displacing said unit, means under control of said displacing means for automatically reversing the direction of movement of said unit, a game-field distinct from said course, a game member to travel said game-field, means to detain the said game-member, and means controllable by said unit to release said game member.

26. In an amusement device, the combination of a unit, a course along which said unit is adapted to travel, hand operated means for displacing said unit, means under control of said hand operated member and operable during the travel of said unit for automatically reversing the direction of movement of said unit, a game-field distinct from said course, a game member to travel said game-field, means to detain the said game-member, and means controllable by said unit for causing the detaining means to release said game member.

27. In an amusement device, the combination of a unit normally positioned to face in a predetermined direction, a course along which said unit is adapted to travel, means for displacing said unit along said course,

means operating relative to said unit to position said unit to face in a different direction, a game-field distinct from said course, a game member to travel said game-field, means to detain the said game-member, and means controllable by said unit for causing the detaining means to release said game member.

28. In an amusement device, the combination of a unit normally positioned to face in a predetermined direction, a course along which said unit is adapted to travel, means for displacing said unit, means under control of the said member for automatically positioning said unit to face in a different direction, a game-field distinct from said course, a game member to travel said game-field, means to detain the said game-member, and means controllable by said unit for causing the detaining means to release said game member.

29. In an amusement device, the combination of a unit, a course along which said unit is adapted to travel, a hand operated member for displacing said unit, means operable at a predetermined speed of operation of the hand operated member for automatically controlling the direction of movement of said unit, a game-field distinct from said course, a game member to travel said game-field, means to detain the said game-member, and means controllable by said unit for causing the detaining means to release said game member.

30. In an amusement device, the combination of a unit normally positioned to face in a predetermined direction, a course along which said unit is adapted to travel, a hand operated member for displacing said unit, means operable at a predetermined speed of operation of said hand operated member for automatically positioning said unit to face in a different direction, a game-field distinct from said course, a game member to travel said game-field, means to detain the said game-member, and means controllable by said unit for causing the detaining means to release said game member.

31. In an amusement device, the combination of a plurality of units normally positioned to face in a predetermined direction, a course along which said units are adapted to travel in a direction which they face, a plurality of hand operated members, each of said members displacing one of said units, means under the control of each of said members and operable at a predetermined speed of operation of said hand operated members for automatically controlling the speed of travel of said units, the direction of movement of said units and the direction in which said units are positioned, a game-field distinct from said course, a game member to travel said game-field, means to detain the said game-member, and means control-

lable by said units for causing the detaining means to release said game member.

32. In an amusement device, the combination of a plurality of units, a course along which said units are adapted to travel, a plurality of hand operated means, means connected with said units to cause said units to travel along the course at a speed which is determined by the speed of operation of the said hand operated means, automatic means for causing a return movement of any one of said units during the operation of the hand operated means, a game-field distinct from said course, a game member to travel said game-field, means to detain the said game-member, and means controllable by a plurality of said units for causing the detaining means to release said game members.

33. In an amusement device, the combination of a plurality of units, a course along which said units are adapted to travel, a plurality of hand operated means, means connected with said units to cause the same to travel along the course at a speed which is determined by the speed of operation of said hand operated means, automatic means for causing any one of said units to face in an opposite direction during the operation of the hand operated means, a game-field distinct from said course, a game-member to travel said game-field, means to detain the said game-member, and means controllable by said units to release said game member.

34. In an amusement device, the combination of a plurality of units, a course along which said units are adapted to travel, a plurality of hand operated means, means connected with said units to cause the same to travel along the course at a speed which is determined by the speed of operation of said hand operated means, automatic means for controlling the speed of any one of said units during the operating of the hand operating means, a game-field distinct from said course, a game member to travel said game-field, means to detain the said game-member, and means controllable by a plurality of said units for causing the detaining means to release said game member.

35. In an amusement device, the combination of a unit, a course along which said unit is adapted to travel, a hand operated member for controlling the displacement of said unit, means interposed between said hand operated member and said unit to vary the speed of travel of said unit, a game-field distinct from said course, a game member to travel said game-field, means to detain the said game-member, and means controllable by said unit to release said game member.

36. In an amusement device, the combination of a unit, a course along which said unit

is adapted to travel, hand-operated means for controlling the displacement of said unit, means responsive to an increased speed of said hand-operated means for causing a decrease in the speed of said unit, a traveling game member controllable by said unit, and value indications correlated with said game-member.

37. In a game device, the combination of a race-course, racers to competitively race along this race-course, a traveling game member, value indications therefor, and means for automatically effecting movement of said game member towards said value indications consequently to the travel of said racers.

38. The structure defined by claim 37, and an electric circuit including a switch which is controllable consequently to the travel of said racers and controls the current of said circuit, the first said means being operatively connected to said circuit and controllable thereby.

39. In a game device, the combination of a course, units to travel along said course, a traveling game member, and means to effect the travel of said game member consequently to the arrival of the first one of said units at a predetermined part of said course.

40. The structure defined by claim 39, means being provided to announce which one of the units first arrives at said predetermined part of the course.

41. In a game device, the combination of a race-course, racers to competitively travel along said race course, a goal, a game member adapted to travel towards said goal but being detained against thus traveling, and means controllable consequently to the travel of said racers for effecting the travel of said game member towards said goal.

42. The combination of a game field, the same including means to indicate different values, a traveling game member to register with any one of the value indications, and means to resist the travel of said game-member towards said value indications, said means being operable to effect movement of said game member towards said value indications.

43. The combination of a game-field including means to indicate different values, said means being divided into distinctive sections and provided with different value-indications, each of said sections being divided into sub-sections representing different values, spaced uprights disposed at the junctions of these sub-sections, a traveling game-member of a width too great to pass between said uprights, whereby two adjacent uprights combine in stopping and holding the game member in registration with the respective sub-division, and means to

effect movement of said game-member towards said value-indications.

44. The structure defined by claim 42, said field including deflectors between the indicating means and the place where the ball is detained before its movement towards the indicating means is effected.

45. The combination of a game-field including means to indicate different values, a game member to travel over said game-field and register with different value indications of said means, a race-course, racers to competitively travel along said race-course, and means controllable by said racers to control said game member.

46. The combination of a game-field including elements to indicate different values, a race-course, racers to competitively travel along said race-course, and means controllable consequently to the travel of said racers for registering with different indicating elements.

47. The combination of a game-field including separate value-indicating elements, a game member to co-operate with the value-indicating elements for designating the respective values, competitive racers, and means controllable consequently to the travel of said racers for controlling said game member.

48. The combination of a game-field, a substantially horizontal race-course, means uniting the game-field and race-course in superposed relation to one another, a game member to travel on said game-field racers to travel competitively on said race-course, and means correlating said game-member with said racer in such relation that one of these moving members controls movement of the other one of these moving members.

49. The combination of a game field and a race-course one of which supports the other, a game-member to travel on said game-field, units to travel on said race-course, and means to control movement of said game-member consequently to the winning of the race by one of said units.

50. The combination of a game-field including separate goals each divided into separate stations which indicate different values, a game-member to co-operate with these stations for designating the respective winners and values of the winners of the

game, and racing units provided with means to correlate them with the respective goals. 55

51. The combination of a unit, a course along which said unit is adapted to travel, means for displacing said unit, means under control of said displacing means for automatically reversing the direction of movement of said unit, a game member, and means controllable consequently to the travel of said unit for effecting movement of said game-member. 60

52. The structure defined by claim 20, a game-field, said game-member being adapted to travel on said game-field, and means correlated with said game-member and one of said units in such relation that the travel of one of these controls the said game member. 65

53. In an amusement device, the combination of a plurality of units, a course along which said units are adapted to travel, a plurality of hand-operated means for displacing said units, a manually operated member for simultaneously unclutching all of said hand-operated means from said units, a game-field constituting a second course and including goals, a game-member adapted to travel on said game-field and register with said goals, deflectors to affect the travel of said game-member, and means controllable consequently to the arrival of any one of said units at the winning point of the first 75 said course so as to control said game-member. 80

54. In an amusement device, the combination of a plurality of units, a course along which said units are adapted to travel, a plurality of hand-operated means for displacing said units, a hand-operated member for simultaneously connecting all of said hand-operated means with the units, means for simultaneously disconnecting all of said hand-operated means from the units, a game-field constituting a second course and including goals, a game-member to travel said game-field and register with said goals, deflectors to affect the travel of said game-member, and means controllable consequently to the arrival of any one of said units at the winning point of the first said course so as to control said game-member. 90

In testimony whereof I affix my signature. 105
MAXIMILLIAN A. MILLER,
